PERMANENT WAVING

Virginia Jean Gentile, Summit, N. J., assignor to
 Beauty Utilities, Inc., Summit, N. J., a corpora-
 tion of Delaware

Application September 21, 1932
 Serial No. 634,097

6 Claims. (CL 132—36)

The invention relates to novel and useful im-
 provements in hair waving, and more particu-
 larly to a novel and useful process for steaming
 and setting the wound tresses, and a preferred
 5 mechanism for practicing the process.

Objects and advantages of the invention will
 be set forth in part hereinafter and in part will
 be obvious herefrom, or may be learned by prac-
 10 tice with the invention, the same being realized
 and attained by means of the instrumentalities
 and combinations pointed out in the appended
 claims.

The invention consists in the novel parts, con-
 structions, arrangements, combinations and im-
 15 provements herein shown and described.

The accompanying drawing, referred to herein
 and constituting a part hereof, illustrate one
 embodiment of the invention, and together with
 20 the description, serve to explain the principles
 of the invention.

Fig. 1 is an elevation, with parts in outline and
 parts broken away, showing one form of mecha-
 nism for carrying out the invention;

Fig. 2 is an elevation of the mandrel or sup-
 25 port for the wound tress or curl;

Fig. 3 is an elevation of the carrier for the
 waving fluid within the curl support;

Fig. 4 is a perspective view of the improved
 30 sachet; and

Fig. 5 is a section on the line 5—5 of Fig. 4.

The invention is directed to improvements both
 in the process and the instrumentalities and
 agencies used in permanent waving, and has for
 35 one of its main objects the production of a super-
 excellent wave, having more lustre and life-like-
 ness, and possessing unusual permanency. These
 and other objects are effected by my invention
 relatively easily and simply, and with a minimum
 40 of dependence on the skill, judgment and vigi-
 lance of the operator.

One of the main objects and functions of my
 invention is to effect and insure adequate steam
 penetration throughout all parts of a curl, irre-
 45 spective of the different sizes of curls, and the
 great variations in thickness of the hair of vari-
 ous customers. A further object of the invention
 is to insure adequate and correct steam penetra-
 tion practically independently of the judgment
 50 and skill of the operator in applying waving liq-
 uid, such as chemical solutions or other suitable
 liquids; and likewise independently of the judg-
 ment and vigilance of the operator in controlling
 or regulating the amount and duration of the
 55 heating action. The invention both by my novel
 process, and by means of the agencies for prac-

ticing same, insures thorough steam penetration
 to all parts of the previously stretched and curled
 hair, with resultant greater excellence and life-
 likeness and permanency of waving, within an
 unusually wide margin with respect to the quan-
 60 tity of waving fluid employed, variations in the
 size of curls, and the relative numbers of hairs
 therein, and in the quantity and duration of heat
 application, and also as regards other varia-
 tions in the conditions and practice in hair
 65 dressing establishments.

By my novel process and the preferred instru-
 mentalities and agencies used in its practice con-
 sidered more in detail, and in carrying out the
 objects stated, steam penetration of the curl is
 effected both interiorly and exteriorly; that is,
 steam is introduced into the stretched and wound
 hair both from the interior outwardly and from
 the exterior inwardly; and the waving fluid or
 other steam producing agency is supplied in suffi-
 70 cient quantity, and in the interior and exterior
 relation indicated, so as to present sufficient mar-
 gin to prevent scorching of any part of the hair,
 and so as to insure the thorough steaming
 throughout the entire curl which is necessary to
 75 effect a thru and thru uniform, complete and
 permanent waving of all the hair in the curl.
 In the preferred manner or form of carrying
 out my novel process, the waving fluid is intro-
 duced into the interior of the wound tress and is
 80 heated and permeates into and thru the tress
 from the interior outwardly; and the waving
 fluid is also preferably concurrently applied ex-
 teriorly to the wound tress and the steam there-
 from penetrates inwardly, and the multi-direc-
 85 tional steam penetration is effected by the ap-
 plication of heat.

Other objects, features and advantages of the
 invention will be set forth in connection with
 the following detailed description of the present
 preferred embodiment of the invention; but it
 will be understood that the foregoing general
 90 description and the following detailed descrip-
 tion as well, are illustrative and exemplary but
 not restrictive of the invention.

Referring now in detail to the embodiment of
 the invention illustrated by way of example in
 the accompanying drawing, the process is ap-
 plied to a tress of hair 1, growing on a head,
 wound spirally or helically under proper tension
 about a support, that type of winding producing
 the best results in hair waving. The support
 upon which the tress is stretched and wound
 may be a mandrel or support 5, such as is shown
 and described in my co-pending application for
 100

110

Hair winding machine Serial No. 467,530, filed July 12, 1930. My said hair winding machine produces a winding or curl of superior uniformity and excellence, and good winding is necessarily a fundamental feature in effecting a superior wave. The support or mandrel 5 (Figs. 1 and 2) is hollow as shown at 7, and at the bottom end is provided with some suitable device for engaging and attaching the tress of hair close to the scalp, preparatory to stretching and winding the tress upon the member 5. The interior steam permeation may be variously accomplished, but as embodied, waving fluid is introduced into the interior of the curl and heated. The introduction of the fluid into the curl may also be variously effected. As embodied, the member 5 is provided with a plurality of very small apertures 9 between the hollow interior 7 and the exterior, in the portion of the member 5 which will be covered by the wound tress. The outer end 13 of member 5 is open, and when my winding machine is used, the mandrel is connected to the winder at this end. In this preferred embodiment, the waving fluid, or the carrier therefor, is introduced within the member 5 at or from this open end.

As now preferably practiced, and as here embodied, the waving liquid is introduced within the curl by means of a carrying device inserted within the member 5, and the interior steaming is effected by heat applied to the liquid within the member 5, whereby steam is generated and permeates the curl throughout its length from the interior outwardly; although the introduction of the liquid and the interior steaming may be otherwise effected so far as concerns the broader features of the invention. Said liquid carrier, as embodied, comprises a slender elongated body capable of carrying the liquid, preferably by absorption, and where a chemical solution is used in the steaming, the carrier may be impregnated with the chemical and later supplied with water, or the chemical solution itself may be absorbed by the carrier. As so embodied a central or supporting core 14 which is preferably of a rustless or non-corrosive material, has exteriorly a filar or other structure or material 15, constituting the liquid carrier, the liquid being absorbed and held between the thread-like or bristle-like members of the part 15. The liquid carrying element may be constructed to absorb and carry a predetermined quantity of fluid, and in other embodiments likewise the quantity of fluid introduced into the curl may be nicely regulated, so as to effect the desired result. This regulation of the interior supply of fluid may be varied for curls of various sizes on the same head. When the carrier is charged with liquid, it is passed into the interior of the foraminous tube 5, and it preferably has an enlarged outer end 16 which serves as a closure for the end of the member 5. Upon the application of heat and generation of steam, this closure when used, will help to create sufficient pressure within member 5 to drive the steam outwardly thru the apertures 9 into the interior of the curl. In the preferred form and as shown in Fig. 1, the tress 17 is wound spirally about the support 5, and a pervious tape 18 is interwound therewith, or thereover, to hold the curl, and especially the hair ends in position, and the outer end of the tape is suitably fastened, and is usually clamped to the support 5.

In carrying out my invention to the best advantage, the waving fluid is applied also to the exterior of the curl, and so far as its details are concerned this may be done in one of the usual

ways. As shown a sachet 23 may be wrapped about the curl, as shown in Fig. 1. The sachet comprises an inner leaf or sheet of felt or other absorptive material, and an outer layer 24 of paper, metal foil or other relatively impervious material. The inner absorbent layer is impregnated with a chemical solution or other suitable waving fluid, and wrapped about the curl, and the outer or relatively impervious layer 24 is wrapped about and encases the whole. The inner end of the sachet is preferably held in place about the bottom of the curl, and just below the inner end of the member 5, by any suitable device such as a clamp 25, and the outer end of the sachet is twisted and crimped or otherwise substantially closed in any desired way.

In thus carrying out my process, the tresses are divided on the head, and are stretched and wound, with practically uniform or definitely varied tension, about the tubular foraminous supports 5, and this uniform or definitely regulated tension and winding constitutes the primary requisite for uniform and super-excellent waving, irrespective of the size of the curl and the number of hairs therein. Furthermore, the waving fluid is applied in proper or regulated quantity or proportion within the curl throughout its length, and in like manner to its exterior throughout its length, preparatory to the steaming. Heat may be applied in any suitable manner and this may be done by means of the usual so-called "waving machine", that is, by the electrical heating sockets, such as 29, encircling the various sachet-enclosed curls, the amount and duration of the heat application being controlled by the operator, or otherwise. In the best practice the application of the heat is largely controlled by the judgment of the operator, but the present invention, by the means and in the manner pointed out, safeguards against damage or ill results which might otherwise result from mistake or neglect on the part of the operator.

In practice in beauty shops, in dividing the hair into strands or tresses preparatory to winding or curling, it is of course impossible to form 120 curls of uniform size, or to get the same amount of hair into each tress and curl; and this variation in itself is conducive to beauty and naturalness in a wave, if thorough steam penetration can be effected. Practically uniform steam penetration and steaming action under those conditions is one of the main objects of the present invention. The penetrative power or effect of the steam from the waving fluid decreases inwardly of the curl, or considered otherwise, the 130 resistance of the tightly-wound hair and intermeshed air to the penetration of the steam into the curl is cumulative; and by simultaneous application of waving fluid both within and exteriorly to the curl, and the resultant steaming 135 and steam penetration in both directions, these negative influences are overcome, and thorough and uniform steaming of the entire curl is insured. As a result there is no dry-heating (i. e. marcelling), nor inadequate steaming, of the inner 140 part of the curl, both of which faults or defects necessarily result in scorching and inadequate and impermanent waving. That is, due to these faults the inner part of the wound tress is dry heated like an ordinary marcel, and 145 after the first shampoo loses its permanency.

The invention further obviates any necessity for attempted close regulation by the operator of the amount of saturation of the usual sachets, with the necessarily unsatisfactory results, as 150

over-saturation creates considerable practical danger of scalding the scalp, and insufficient saturation results in simply marcelling the interior of the curl, or by excessive application of heat, possible scorching and serious injury to the hair. The combined interior and exterior action of the present invention, in addition to the advantages already indicated, gives assurance of thorough steaming and therefore perfect waving 5 of thick curls, and prevents total evaporation and the danger of burning the hair as often happens when the moisture is exhausted and the heat continued. The margin of time permitted or provided by this invention, would allow an operator to over-steam for a comparatively long period without actually going over the danger line, and thus practically removes this danger in the cases of ordinary careful and competent operators. It also removes to a large degree the 10 necessity for the general exercise of judgement and special skill on the part of the operator. In view of the various factors pointed out, the present invention practically insures the desired 15 lustrous, natural and lasting wave, well within 20 the limits of skill, judgment and attention of 25 ordinary operators.

The invention provides also an improved sachet, or exterior waving fluid applicator having 30 as its novel feature means for absorbing or damming any surplus hot liquid and preventing possible seepage thereof downwardly, and consequent scalding of the scalp. As embodied, the sachet is shown comprising an inner absorbent sheet or leaf 31, which absorbs the waving fluid, 35 and it is attached to an exterior relatively impervious sheet or layer 24, which may be of paper, foil or the like. As embodied, the sheet or member 24 has attached to its inner lower edge a transversely-disposed layer 33, which is 40 preferably both absorbent and compressible, such as a fibrous material. When the sachet is wound about the curl and the lower end is clamped thereabout, the member 33 is brought closely 45 around the bottom part of the curl, and is preferably closely compressed, and acts as an absorbent or a dam, or both, to guard against the downward flow of hot liquid or steam.

The invention in its broader aspects is not limited to the particular exemplary manner set forth for carrying out the process, nor to the specific form of means and instrumentalities described; as departures may be made therefrom without departing from the principles of the 50 invention or sacrificing its chief advantages.

What I claim is:

1. Process of permanently waving hair which comprises winding a tress on a hollow foraminous support, moistening an absorbent lotion carrier with hair waving solution, introducing said moist carrier into the interior of the support and heating the solution to vaporize it and steam the curl. 80

2. The process of permanently waving hair which comprises winding a tress on a support, moistening an absorbent member with hair waving solution, introducing said absorbent moist member into the interior of the support and within the curled tress, and vaporizing the waving solution by heating the tress and support to steam the curl. 85

3. Process of permanently waving hair which comprises winding a tress on a hollow foraminous curling rod having an open end remote from the roots of the hair, introducing an absorbent lotion carrier which is moist with hair waving solution into the open end of said curling rod and heating and vaporizing said waving solution. 95

4. Process of permanently waving hair which comprises winding a tress on a hollow foraminous curling rod in a helical curl from the scalp end outwardly, the end of said curling rod remote from the scalp being open, moistening an absorbent lotion carrier with hair waving solution and introducing said moist carrier into the open end of the curling rod and thereafter heating the waving solution by applying heat about the exterior of the curled tress. 100

5. Process of permanently waving hair which comprises winding a tress on a hollow perforate curling rod, moistening an absorbent lotion carrier with hair waving solution, inserting said moistened carrier within the curling rod, wrapping a lotion carrier moistened with waving solution about the exterior of said curled tress and heating the tress to vaporize the waving solution and steam the curl both exteriorly and interiorly. 110

6. Process of permanently waving hair which comprises winding a tress on a hollow foraminous curling rod, surrounding the curl with a lotion carrier moistened with hair waving solution, introducing a lotion carrier moistened with hair waving solution into the interior of the curling rod, and heating the waving solution in the exterior lotion carrier to vaporize the solution in both said carriers. 115
